James Edwin Mead, Chatham, N.J.
(28 Burgess Place, Wayne, N.J. 07470)

Filed Mar. 5, 1973, Ser. No. 338,181

Term of patent 14 years

Int. Cl. D12—02

U.S. Cl. D12—27

FIG. 1

FIG. 2

FIG. 3

FIG. 4

FIG. 1 is a front elevational view of a mobile trash receptacle, showing my new design;

FIG. 2 is a left end elevational view;

FIG. 3 is a top plan view; and

FIG. 4 is a right end elevational view.

The elevational view of said mobile trash receptacle opposite that seen in FIG. 1 is a mirror image thereof except for showing in elevation the rectangular hinge butts, illustrated in side view in FIGS. 2 and 4, and in plan in FIG. 3.

I claim:

The ornamental design for a mobile trash receptacle, substantially as shown and described.
